MEDICINE SPOON

Joseph P. Takach, West New Brighton, Staten Island, N. Y.

Application January 9, 1940, Serial No. 313,132

3 Claims. (Cl. 30—326)

This invention relates generally to spoons and more particularly to medicine spoons.

Among the objects of the present invention is the provision of a medicine spoon structure in which the spoon may be loaded with a medicine or other similar material and then closed so that the spoon may be inverted without discharging the contents thereof.

Another object herein lies in the provision of a medicine spoon structure in which the valve element thereof is easily operated so that the same may be readily opened within the patient's mouth and the medicine prepared to be discharged therefrom.

Another object herein lies in the provision of a medicine spoon which may be readily disassembled for cleaning purposes and in which all the parts thereof are readily accessible, so that said spoon may be maintained in a sanitary condition.

In accordance with the present invention another feature thereof lies in the fact that the present improved medicine administering spoon is simple in construction and may be manufactured in large quantities at low cost so that the same may have a wide distribution among the population.

It is a well known fact that considerable difficulty is encountered when administering drugs to patients, especially if the patients are children. Frequently, the drug or similar preparation has an unpleasant taste and in the child's efforts to avoid being fed the same, the medicine is spilled resulting in considerable untidiness, bother and loss of dosage.

In accordance with the present invention, it is necessary only to actuate the valve thereon, into an open position thereof, to introduce into the spoon the proper dose, close the valve, insert the entire closed spoon into the patient's mouth, then open the valve allowing the contents of the spoon to enter the mouth. Since in applicant's improved construction, the open end from which the medicine flows out is at the tip of the spoon, said open end will be disposed toward the rear of the mouth when the spoon is inserted into the mouth of the patient. In this manner, it is possible to avoid depositing very much of the drug on the tongue so that the taste of the drug where the same is distasteful is not perceived by the patient to as great an extent.

These objects and other incidental ends and advantages will more fully appear in the progress of this disclosure and be pointed out in the appended claims.

In the drawing in which similar reference characters designate corresponding parts throughout the several views:

Figure 1 is a view in perspective showing a first embodiment of the invention.

Figure 2 is an enlarged transverse vertical sectional view as seen from the plane 2—2 on Figure 1.

Figure 3 is a schematic transverse sectional view as seen from the plane 3—3 on Figure 1.

Figure 4 is a view taken similarly to Figure 1, and showing a second embodiment of the invention.

Figure 5 is a vertical transverse sectional view as seen from the plane 5—5 on Figure 4.

Turning now to the first embodiment of the invention illustrated in Figures 1 to 3 inclusive of the accompanying drawing, the device for administering drugs, or similar material, is generally indicated by numeral 10 and comprises generally a spoon 11 and a valve member 12.

The spoon 11 includes a bowl portion 13, a cover plate or top wall 14 and a handle 15. The top wall 14 is preferably integrally connected at 25 the peripheral edge thereof with the peripheral edge of the bowl portion 13. The top wall 14 is provided at the forward portion thereof with an irregular shaped filling and discharging opening or orifice 16; at the rear portion with air vents 17; and between the air vents 17 and the orifice 16, with a forward guide element engaging orifice 18. The forward edge of the orifice 16 is preferably coterminous with the forward or leading edge 19, while the rear edge thereof is rounded 35 and is provided with a cleaning indentation or notch 20. The handle 15 is preferably elongated and has the longitudinal side edges thereof parallel. The end of the handle is preferably bent downwardly and forwardly to form the hook portion 21. The handle 15, forwardly of the hook portion 21, is provided with a pair of oppositely disposed notches 22, only one of which is seen in Figure 1, but which are indicated by the dotted lines in Figure 2. The notches 22 are disposed 40 on the handle 15 at a point to the rear of the fingers 23 when they are in the normal retracted position thereof as will be more fully described hereinbelow. The upper flat surfaces of the handle 15 and the top wall 14 are preferably 45 co-planar.

The valve member 12 is preferably an elongated flat plate, the under surface of which is smooth so that the same may make a good sliding fit with the upper surface of the top wall 14 50 and the handle 15. The forward portion of the

valve member is transversely enlarged to form the valve plate 24, which is slightly wider than the orifice 16. The valve plate 24 is provided with a longitudinally disposed slot 25, the forward end of said slot being disposed at a sufficient distance from the leading edge 26 so that when the valve member 12 is in the retracted or open position thereof material may flow through the orifice 16 unobstructed. The rear end of the slot 25 is disposed with relation to the edge 26 so that when the valve plate 24 is in the advanced or closed position thereof the edge 26 may be coterminous with the edge 19 so that no leakage of fluid material from the spoon bowl 13 may occur. The valve plate 24 is maintained in operative relation and contact with the top wall 14 by the forward guide element means preferably a resilient washer and a headed screw 27 which threadedly engages the threaded orifice 18. The rear portion of the valve member 12 is provided with the pair of downwardly and inwardly bent fingers 23; while the rear end of the member 12 is upwardly and forwardly bent to form the valve hook portion 28. The fingers 23 slidably engage the longitudinal side edges and adjacent portions of the under surface of the handle 15, and are so disposed on the valve member 12 that when the screw 27 contacts the forward end of the slot 25, said fingers will not reach the notches 22.

Operation of the first embodiment of the invention here follows. With the valve member 12 in the retracted or open position thereof as indicated by the full lines in Figure 1, the device 10 is preferably held in a level position. The hook portions 21 and 28 are conveniently grasped. Preferably the middle finger engages the hook 21 while the thumb and index finger engage the hook 28. The desired amount or dose of medicine or other material is placed within the bowl portion 13 through the orifice 16. This operation is facilitated by the vents 17 acting to prevent the formation of any air pockets in the rear of the bowl portion 13. The valve member 12 is now slid to the advanced or closed position thereof as indicated by the dot dash lines in Figure 1. In this position the valve plate 24 closes both the orifice 16 and the vents 17. The bowl portion 13 is next partially or fully inserted into the mouth of the patient and the spoon is tilted. The valve member is shifted to the open position and the contents are allowed to flow through orifice 16 into the patient's mouth. The vents 17 prevent a vacuum forming in the device.

When it is desired to fully clean the device 10 it is only necessary to remove the washer and screw 27, slide the valve member 12 rearwardly until the fingers 23 may be lifted through the notches 22. With the parts thus separated, they may be individually washed and sterilized. A suitable swab or brush may be inserted through the orifice 16 and this operation is facilitated by the notch 20 permitting more convenient access to the interior of the device.

In reassembling the parts, the above described procedure is reversed. The screw 27 may be adjusted to permit a proper amount of friction in moving the valve member 12, and if turned tight will secure the valve member in any desired position.

Turning now to the second embodiment of the

invention illustrated in Figures 4 and 5 of the accompanying drawing indicated generally by numeral 110, the same comprises generally a spoon 11 and a valve member 112.

5 The principal difference between the first embodiment and the second embodiment lies in the provision of a depression or channel 130 in the top wall 114 having parallel side edges. The valve member 112 is provided with an offset bend 10 at 131 so that the lower surface thereof may have a sliding fit with the upper surface of handle 115. The channelled construction of the top wall 114 provides a more accurate longitudinal guide means for the outer longitudinal edges of the valve plate 124 and a tighter seal between the valve plate 124 and the top wall 114 adjacent the orifice 116. The other parts are given corresponding reference characters in the "one hundreds."

20 By reason of the bend at 131, in removing the valve member 112 for cleaning purposes, it is necessary to raise the valve plate 124 slightly after the screw 127 has been removed. This is permitted by allowing sufficient clearance between the fingers 123 and the handle 115.

25 It may thus be seen that there has been disclosed a novel and useful spoon for administering medicine and other materials. By suitable changes in the general size of the device the same may be readily adapted for use with infants, children, adults and animals. The device is convenient and sanitary and may be constructed at low cost.

30 I wish it to be understood that I do not desire to be limited to the exact details of construction shown and described, for obvious modifications will occur to a person skilled in the art.

I claim:

40 1. A medicine administering device comprising: a spoon; a top wall on said spoon; said top wall having a relatively large orifice in the forward portion thereof, and a relatively small orifice in the rear portion thereof; a valve plate shiftably disposed with relation to said top wall and adapted in one position thereof to allow a 45 free passage through both of said orifices and in another position to close both of said orifices.

2. A medicine administering device comprising: a spoon; a top wall on said spoon; said top wall having a relatively large orifice in the forward portion thereof and a small orifice in the rear portion thereof; a valve plate for exposably covering said orifices and having a slot therein, said valve plate being shiftably disposed with relation to said top wall and adapted in one position thereof to expose said forward orifice to allow free passage therethrough, while said slot is positioned at the small orifice to prevent obstructing pressure conditions within the spoon.

3. A device of the class described comprising: 60 a spoon; a top wall on said spoon having an orifice therein, a valve member slidably disposed with relation to said top wall and adapted in the open position thereof to allow a free passage through said orifice, and in another position to close said orifice; said valve member including a longitudinally disposed slot and means detachably engaging said top wall and cooperating with said slot to maintain the valve member in proper slidable relation with said wall.
